UNITED STATES PATENT OFFICE.

DAVID M. SWAIN, OF STILLWATER, MINNESOTA, ASSIGNOR OF TWO-THIRDS
TO SEYMOUR, SABIN & CO., OF SAME PLACE.

BOILER FOR PORTABLE ENGINES.

SPECIFICATION forming part of Letters Patent No. 234,627, dated November 16, 1880.

Application filed September 1, 1880. (No model.)

To all whom it may concern:

Be it known that I, DAVID M. SWAIN, of Stillwater, in the State of Minnesota, have invented certain new and useful Improvements 5 in Boiler-Furnaces for Portable Engines; and I do hereby declare the following to be a full, clear, and exact description of the invention, such as will enable others skilled in the art to which it appertains to make and use the same, 10 reference being had to the accompanying drawings, and to letters of reference marked thereon, which form a part of this specification.

Figure 1 is a longitudinal section of my improved boiler-furnace, and of a boiler combined therewith, some of the ordinary parts of an engine being also shown. Fig. 2 is an end view. Fig. 3 is a transverse vertical section through the furnace and boiler. Fig. 4 is a vertical longitudinal section of the devices for 20 supplying water to the furnace ash-box. Fig. 5 is a perspective view of the furnace grates.

One part of the invention relates to the combination, with the furnace, of an improved device for guiding the fuel as it is being introduced.

Another part of the invention relates to the combination, with the furnace fire-box, of a front wall for said box, provided throughout with perforations, whereby currents of air are 30 introduced to prevent the ashes from escaping upwardly from the furnace.

Another part of the invention relates to the combination, with the furnace and the fire-flues; of a peculiarly-constructed returning-chamber at the front end of the boiler.

Another part of the invention relates to the combination, with the furnace, of a peculiarly-constructed ash-box situated directly beneath the fire-box and arranged to hold a body of 40 water for quenching the ashes.

Another part of the invention relates to the combination, with the furnace and the ash-box, of a peculiarly-constructed feed-water heater and devices for conducting the water of condensation from said heater to the ash-box.

The invention relates also to various detail improvements, which shall be hereinafter fully set forth.

In the drawings, A represents the fire-box, 50 situated at the rear end of the boiler and constructed as large as possible.

From Figs. 1 and 3 it will be seen that the wall of the fire-box is so surrounded by the outer wall, A, of the boiler that the water shall be in contact with the fire-box, not only at its upper side, but also in the rear of the box, as shown at A², and at the sides of the box, as shown at A³ A³.

At the bottom of the fire-box the fire-grate C is placed. It is formed of several (preferably two) sections, which are provided with journals c c, projecting from the outer cross-bars of the grate-section, and journals c' c' on the inner cross-bars. The journals c' c' are mounted in a bracket or suitable support, C', 60 at the inner end of the fire-box, and the journals c c are mounted in apertures or bearings formed in the front wall of the box.

C³ C³ are spur-wheels of equal diameter, attached, respectively, to the outer ends of journals c c. The wheels mesh with each other, and by means of crank c², attached to one of them, they can be rotated so as to simultaneously turn the grate-sections C C, and thus the ashes and cinders can be instantly dropped 70 into the ash-pan D.

I am aware that heretofore use has been made of gear-wheels in combination with grates, each of which was constructed with four or more radial plates, and I do not claim 80 such construction as my invention; but it will be seen that both sections of my improved grate are situated in the same horizontal plane when in use, and therefore that when they are rotated or tilted there is no danger of catching cinders or masses of hard matter between them, and thus prevent their being emptied. Each grate has but two wings extending from the axial line.

This ash-pan is constructed with the central part, d, of the bottom substantially horizontal, and the end parts, d' d', somewhat inclined, so as to have a shallow receptacle which shall hold a quantity of water sufficient to quench the ashes, and from which the ashes 90 can be readily removed by a rake, D'.

D² D² are openings at the ends of the ash-pan through which the rake can be inserted and the refuse can be withdrawn.

The means which I have devised for giving 100 a constant supply of water to the ash-pan will be fully described hereinafter.

When wood or coal is to be used as fuel, the ordinary door E, hinged to the front of the fire-box, is employed. When straw is to be used as fuel, a feed-funnel, E', is secured in place in the doorway, and through the funnel the straw is introduced. When the straw is passed into the fire-box on horizontal lines it tends to be carried so far toward the inner end of the box as to interfere very largely with perfect combustion. In order to obviate this I have devised a feed-funnel which shall guide the straw directly downward toward the outer end of the grate as soon as it has entered the box.

By examining Fig. 1 it will be seen that the top or upper wall of the funnel is curved downward to a line on or below the center of the funnel, and that the bottom or lower wall does not extend beyond or inside of the front of the fire-box. This construction permits the easy insertion of the straw, and at the same time guides it directly downwardly toward the outer end of the grate, insuring that the fuel shall be subjected to the action of combustion to the greatest extent possible. Moreover, I have found, when using the devices in the relation described, that the straw is ignited before reaching the grate, and this early igniting obviates a defect very common in straw-burning engines—namely, the leaving of hard lumps of unburned straw.

The front wall, F, is provided with perforations f f, situated closely together over the whole of the front, and the air necessary for supporting combustion is supplied through these perforations. When air is thus supplied no ashes or light cinders are suspended in the fire-box or carried to the fire-flues or boiler-flues, as is the case when combustion is supported by a strong upward draft through the grates. The front F is also provided with a sliding draft-door, F'.

In order to utilize to a greater extent than has heretofore been done all of the heat generated below the boiler, I have devised a peculiar construction and arrangement of fire-flues and boiler-flues. The fire-box is provided with an arched top, as shown at A⁴. With the arched part of the box a large fire-flue, G, is arranged to communicate. This fire-flue is made tubular in order to make available as much heating-surface as possible. I combine with the central flue, G, supplemental lateral fire-flues G', which are also tubular in form, and they enable me to utilize, for heating the water in the boiler, the products of combustion as they leave the fire-box.

At the front end of the engine I attach a returning device of peculiar construction, as shown at I. It is a tight chamber which is at the bottom of a width equal to the outside distance of the supplemental fire-flues G' G', and is constructed to expand both laterally and outwardly as it is carried up, so as to deliver the products of combustion to the return-flues with the least exposure and waste. Moreover, it is so formed that its inner surface at

all points shall be curved, as shown in the drawings, and without any angles or corners to catch the ashes or cinders. Should any ashes or other undesirable material settle in the returning-chamber they will at once be carried down to the fire-flue, (owing to the nature of the inner surface described,) whence they can be readily withdrawn. As the wall I' of the returning-chamber I is cornerless and rounded in the manner shown, the currents from the fire-flues pass through the chamber to the return-flues uniformly and with but little resistance.

N represents a box or chamber of a length nearly equal to that of the engine, and attached thereto immediately below the steam chest and cylinder. It is divided into two compartments by the partition N' extending longitudinally over a greater part of the interior of the heating-box N. It is provided with a port, n, communicating with the exhaust-port of the engine and arranged to admit the exhaust-steam to the upper of the compartments.

O is a discharge-pipe communicating with the lower of the chambers in the heating-box, and with the smoke-stack by an upwardly-inclined portion, O'. The exhaust-steam passes along the upper chamber to the throat n', whence it passes back in the opposite direction, through the lower chamber and through the discharge-pipe O, to the smoke-stack. The pipe O passes into the chamber at a point considerably below the bottom, so that no water of condensation can pass to the smoke-stack. Said water of condensation is conducted to an orifice, Q, beneath the port n, from which it is carried by a pipe, R, to the ash-pan.

By means of these devices I am enabled to furnish the ash-pan with a constant supply of water to take the place of that lost by evaporation and otherwise.

The returning-chamber I is so arranged that the inner surface of the bottom part is substantially coincident with the bottom of the central fire-flue, G, so as to insure that the cinders and other heavy particles that may reach said chamber shall fall back to the fire-flue, from which they can be readily withdrawn.

I do not herein claim any of the specific improvements in the boiler which I may have shown, as I prefer to make these the subject-matter of another application.

What I claim is—

1. In a portable engine, the combination, with the boiler-furnace having the front vertical wall, F, of the detachable feed-funnel E', when constructed to have the upper wall curved downward and the bottom or lower wall extended to but not beyond the front wall of the fire-box, as set forth.

2. In a portable engine, the combination, with the boiler-furnace, of the front wall, F, when it is provided throughout with perforations f f, substantially as and for the purposes set forth.

3. In a portable engine, the combination, with a boiler-furnace, of the ash-receptacle D, which

is situated directly beneath the fire-box of the furnace, and is provided with openings at both ends, and is constructed to hold a body of water, substantially as set forth.

- 5 4. In a portable engine, the combination, with the boiler-furnace, of the ash-receptacle D, when constructed with the apertures D² at each end, and the inclined parts d' d² of the bottom, substantially as set forth.
- 10 5. In a portable engine, the combination, with the boiler-furnace, the ash-receptacle D, and

the feed-water heater N, of devices arranged to conduct the water of condensation from the feed-water heater to said ash-receptacle, substantially as set forth.

In testimony that I claim the foregoing I have hereunto set my hand. ¹⁵

DAVID M. SWAIN.
